UNITED STATES PATENT OFFICE

OLOF J. GRANDAHL, OF HARTFORD, CONNECTICUT

DESIGN FOR A VALVE FIXTURE

Application filed December 9, 1931. Serial No. 42,010. Term of patent 14 years.

To all whom it may concern:

Be it known that I, OLOF J. GRANDAHL, a citizen of the United States, and a resident of Hartford, in the county of Hartford and State of Connecticut, have invented a new, original, and ornamental Design for Valve Fixtures, of which the following is a specification, reference being had to the accompanying drawings, forming part thereof, in which—

Figure 1 is a top view of a valve fixture embodying my new design.

Figure 2 is a front view of the same.

Figure 3 is an end view.

I claim:

The ornamental design for a valve fixture, as shown.

OLOF J. GRANDAHL.
